(57) **CLAIM**

I claim the ornamental design for a woofer, as shown and described.

DESCRIPTION

FIG. 1 is a perspective view of the woofer showing my novel design;

FIG. 2 is a right-side view thereof;

FIG. 3 is a left-side view thereof;

FIG. 4 is a front view thereof;

FIG. 5 is a rear view thereof;

FIG. 6 is a bottom view thereof;

FIG. 7 is a top view thereof;

FIG. 8 is a front/side perspective view thereof; and,

FIG. 9 is a rear perspective view thereof.

The broken lines depicting a plurality of controls and/or connectors in FIGS. 5 and 9 are for illustrative purposes only and form no part of the claimed design.
